UNITED STATES PATENT OFFICE.

HARRY J. JOACHIM, OF WEBSTER GROVES, MISSOURI.

SEAT COVERING.

Application filed July 14, 1927. Serial No. 205,563.

This invention relates to seat coverings and is herein illustrated as embodied in a covering of the same general character as that illustrated in United States Letters 5 Patent No. 1,436,459 granted Nov. 21, 1922, in the name of T. Reece.

A covering of the type disclosed in said Letters Patent comprises, broadly speaking, a seat section and a back section which are 10 pivotally secured along adjacent edges, and arranged to extend over the bottom and back portions of a seat such as that of an automobile, a chair, etc. By reason of the fact that the two sections are pivotally secured 15 together they may be collapsed or folded when not in use as a prevention against the accumulation of dust thereon.

Seat coverings of the aforementioned type have been manufactured and sold widely, and 20 while they have proved satisfactory in many respects it has been found that upon being submitted to constant use certain areas of the covering sections are apt to become worn and frayed, whereas other areas remain comparatively intact and undamaged. This 25 condition is brought about by reason of the fact that when used in the seat of an automobile, or the like, the ends of the covering sections that extend adjacent to the front 30 edge of the seat and to the top edge of the back of the seat are subject to more wear than are the secured adjacent ends that lie in the crevice of the seat at the line of junction between the bottom and the back of the 35 seat. When the covering becomes worn in the aforementioned manner the frayed areas no longer afford protection to the clothes of the user and the frayed ends of the fibres are likely to snag or tear clothing made of 40 thin material. Consequently, it becomes necessary to discard the covering when it reaches this stage, notwithstanding the fact that it is damaged only in localized areas. It will therefore be appreciated that by 45 avoiding the concentration of wear upon these areas the useful life of such a covering would be substantially prolonged.

Accordingly, the present invention has for an important object thereof the provision 50 of an improved seat covering which may be adjusted upon occasion to secure an even distribution of wear throughout the entire surface area of the covering.

With a view to carrying out this object an 55 important feature of the invention resides in the provision in a seat covering having a

plurality of alined sections of means for connecting together said sections in such a manner that the sections may be reversed to interchange the relative location of the inner adjacent edges and the outer opposite edges of the alined sections. In the illustrative embodiment of the invention this feature is carried out by means of an apron having its opposite ends secured to the two sections at equal distances from the opposite ends of each section along lines extending transversely to the lengthwise dimension of the covering. By virtue of such a construction the two sections of the covering may be reversed to bring into adjacent relation edges that formerly defined the opposite extremities of the covering.

These and other features and objects of the invention will become apparent from a 75 reading of the following description and on inspection of the accompanying drawings, in which

Fig. I is a plan view showing the seat covering occupying a flattened or extended position.

Fig. II is a side elevational view showing the covering in the extended position and indicating in dotted lines the position of the covering when in use in a seat.

Fig. III is a view inside elevation showing in full lines the position occupied by the covering when being used, and indicating diagrammatically, by means of dotted lines, the manner in which the sections of the 90 covering may be reversed.

Fig. IV is a view in side elevation showing the covering applied to a seat.

As shown in the drawings, reference numerals 10 and 12 indicate two rectangular sections of a seat covering which may be composed of flexible interwoven straw or other suitable material. The two sections 10 and 12 are connected together by means of an apron 14 having its opposite ends secured to the sections 10 and 12 along the lines 16 and 18, respectively, these lines being located midway of the length of the sections and extending transversely to the longitudinal dimension of the covering. The apron or connecting means 14 is made from any suitable material, such, for example, as fabric, and is of sufficient flexibility to permit the sections 10 and 12 to be moved with ease into their extended, seated or collapsed positions.

For the purpose of clarity in describing

the reversible character of the covering, the adjacent edges of the sections, as shown in Fig. IV, are indicated by the reference characters *a*, *b*, and the outer edge portions in 5 the same illustration are indicated by the reference characters *c*, *d*. As hereinbefore pointed out, a covering positioned within a seat as indicated in Fig. IV is peculiarly subject to wear along the outer edge areas designated at *c*, *d*, and, to the end of preventing such wear the sections 10 and 12 are bordered with marginal reinforcing strips 20.

Notwithstanding the provision of the reinforcing strips 20, continued use of the 15 covering causes the edges *c* and *d* to become worn and frayed, thereby ceasing to afford protection at those areas to the clothes of the user, and, in the event that the fibre of which the covering is made is sufficiently 20 tough, another danger presents itself, namely, that the frayed ends are likely to become caught upon, and snag or tear, the clothes of the user. By way of comparison it will be appreciated that the rear adjacent 25 edges *a*, *b* of the covering, located within the crevice of the seat, are subject to very little wear, and have no cause for becoming worn and frayed as do the areas adjacent to the outer edges. As stated above, 30 the present invention contemplates reversing the positions of the sections 10 and 12 in such a manner that the location of the inner edge areas, *a* and *b*, may be interchanged with the outer edge areas, *c* and *d*, to produce an equal distribution of wear through 35 the entire surface area of both sections.

In the illustrated embodiment of the invention this feature is carried out by securing the apron 14 to the sections 10 and 12 40 in such a manner that the sections may be pivotally reversed relatively to the apron as shown in Fig. III. As there illustrated, the section 10 is, upon removal of the covering

from the seat, free to swing downwardly 45 into the position illustrated in dotted lines at the bottom of the figure, and may then be grasped manually and pivotally turned into the horizontal position illustrated in dot and dash lines at the left in said figure. Similarly the section 12 may be reversed by 50 rotating it about the line of stitch 18 through 180° to bring it into a vertically extending position, illustrated in dot and dash lines. When a reversal of this sort has been effected, it will be observed that the edge 55 areas *d* and *c*, which were formally located at the outer extremities of the covering, now lie adjacent to each other, and that the former inner adjacent edge areas, *a* and *b* now constitute the outer edge areas of the 60 covering. Thus it will be seen that a reversal has been effected which interchanges the worn portions of the covering with the unworn portions, thereby substantially prolonging the life of the covering. 65

While the invention has been described herein as comprising a plurality of sections either of which is reversible, it is to be understood that the invention contemplates similar constructions, such, for example, as 70 one in which only one of the sections is reversible relatively to the other.

Having thus described my invention, what I claim as new and desire to secure by Letters Patent of the United States is: 75

A collapsible seat covering comprising a plurality of substantially rectangular aligned sections connected together by means of an apron having its opposite ends secured to the two sections approximately mid-way of 80 the length of each section along lines extending transversely to the lengthwise dimension of the covering.

In testimony that I claim the foregoing I hereunto affix my signature.

HARRY J. JOACHIM.
